John W. Hill

UNITED STATES PATENT OFFICE.

JOHN W. HILL, OF CINCINNATI, OHIO.

GRAIN-METER.

SPECIFICATION forming part of Letters Patent No. 241,659, dated May 17, 1881.

Application filed January 20, 1881. (No model.)

To all whom it may concern:

Be it known that I, JOHN W. HILL, of Cincinnati, in the county of Hamilton and State of Ohio, have invented certain new and useful 5 Improvements in Grain-Meters, of which the following is a specification.

My invention is in the nature of an improvement upon an automatic grain-weigher for which Letters Patent were granted me April 15, 10 1873, May 18, 1880, and May 25, 1880, (reissue); and it consists, first, in connecting the "balance-bobs" to the scale-beam by means of links or their equivalents, whereby the motion of the bobs is coincident with and controlled by the 15 rise and fall of the beam; second, in providing upon the mouth of the spout adjustable stops against which the main cut-off closes, whereby the stricture or opening through which the final quantity of grain flows may be adjusted 20 to the grain used in the weigher; and, third, in constructing the weighing bucket or pan of two separate receptacles, and providing said bucket with counterbalanced sectors or a sector, and arranging said receptacles, with relation to each other and to the sector or sectors, 25 in such a manner that the rate of descent of the full receptacle while discharging the weighed load of grain will be gradually retarded by the change in position of the centers of gravity of the discharging and empty receptacles.

In the accompanying drawings, Figure 1 is an elevation of a grain-weigher containing the improvements herein described. Fig. 2 is a detached view, in elevation, of the balance-bob, connecting-link, and sector of the scale-beam. Fig. 3 is a detached view of the mouth of the spout, showing the valves or cut-offs, and the adjustable stops against which the main cut-off closes, and Fig. 4 is a detached view of the 30 weighing-bucket and counterbalanced sector. Fig. 5 is a section of the spout and main cut-off.

Similar letters of reference indicate similar parts.

45 A is the frame of an automatic grain-weigher containing the balancing-beam B, balancing-weight B', suspenders C C, weighing-bucket D, and spout G.

c is an arm upon the suspender C, upon 50 which is pivoted the gravitating latch E.

e is a stud or detent secured to the latch E, which engages with the notch f of the sector F.

The devices c, E, e, F, f, and a for retaining the bucket in position for the reception of and for causing the automatic discharge of the 55 weighed grain are, with the exception of the device F, fully described in my former patents of April 15, 1873, and May 25, 1880, referred to.

H H' H' are the arms by which the cut-offs h and h' are suspended from and actuated 60 by the rock-shaft k.

K is the balance-bob, of which there are usually two, one upon each side of the spout G.

L is the link, usually of hardened steel, attached to the beam B by the hardened pivot or 65 stud l, and to the short arm of the balance-bob by the hardened pivot l'.

It will be observed that by means of the link L and pivots l and l' the connection of the bob K with the scale-beam B is positive, and 70 that the motion of the bob is controlled, in time and quantity, by the motion of the beam.

g is the stop, of which there are usually two, one upon each side of the spout G, and attached thereto by the screws g', and made adjustable in position by means of the stop g''. By sliding the stops in one direction and securing them in position, the stricture G' between the edge of the main valve h and side of the spout G is adapted to large grain—as 80 corn and oats—and by sliding the stops in an opposite direction, the stricture is narrowed to adapt it to small grain—as flaxseed, rye, and clover.

Experience has shown that an uniform slot 85 or stricture, G', through which the final quantity of grain is taken will not answer equally well with all grains, and that the stricture must be adapted to the kind of grain passed through the machine. In scales or weighers 90 for warehouses where all kinds of grain are to be weighed the stops g may be adjusted by tempering-screws with indexed hand-wheels, which in one position adjust the slot for wheat, and in another for corn, and in another for flax- 95 seed, &c., the essential requisites of the stops being adjustable in position to adapt the stricture G' to the various grains used with the machine.

The bucket D consists of two receptacles, D' 100 D', each being constructed to contain, as delivered from the spout G, a convenient quantity of grain—as ten pounds, one bushel, or five bushels. The receptacles D' D' are precisely

alike in form and dimensions, and are set to receive and dump grain right and left.

The sector F is provided with a counterbalance, f' , of such weight as will practically produce an equilibrium of the sector in any position in the arc which it describes. By reason of the balanced sector, and peculiar disposition of the receptacles D' D', the full or loaded receptacle of the bucket descends quicker upon the lifting of the stud or detent e from the notch f , and strikes the stop S with less impact than with the construction of bucket shown in my former patents referred to, where the weight of the sector operates to retard the bucket during the first half of its travel, when the stud e of the gravitating-latch E is lifted from the notch f , and to accelerate the motion of the bucket during the last half of its travel, and causes the bucket to strike the stop with considerable impact.

There are other practical advantages obtained by the construction of bucket herein shown, such as freely discharging the contents of the loaded receptacle by inversion when it strikes the stop S; by bringing the center of gravity of the receiving receptacle more nearly under the mouth of the spout, and by utilizing a larger percentage of the full section of the receptacle D' with the weighed load of grain.

I have described my invention as an improvement upon a certain grain-weigher for which Letters Patent have been granted to me; but it is obvious that the principle of my invention is not limited to automatic grain-weighers, as it may be applied to machines for the automatic weighing or measuring of spirits, liquids, and many substances which are capable of being spouted.

Having described my invention, what I claim is—

40

1. In a machine for the automatic weighing of grain and other substances, the combination, with the weighing-beam B, of the balance-bobs K, positively connected to said beam, whereby the motion of the bobs is caused to be coincident with and positively controlled by the rise and fall of the beam, substantially as and for the purpose set forth.

2. In an automatic weighing-machine, the balance-beam B and the balance-bob K, connected by means of the link L and pivots l l' , substantially as and for the purpose described.

3. In a machine for automatically weighing flowing substances, the combination, with the hopper, of the cut-off h , and the adjustable stop g , arranged to limit the motion of the cut-off to vary the width of the stricture or slot G, essentially as set forth.

4. In a machine for the automatic weighing and dumping of grain and other substances, the combination of the dumping-bracket D, consisting of the two equal connected receptacles, D' D', the counterbalanced sector F, having notches f f' , and the gravitating-latch E, having a stud or detent, e , to engage with said notches, substantially as and for the purpose described.

In testimony whereof I have signed my name to the foregoing specification in the presence of two subscribing witnesses.

JOHN W. HILL.
